UNITED STATES PATENT OFFICE.

GEORGE W. YOUNKMAN, OF DENVER, COLORADO.

FIRE-ESCAPE.

No. 826,702.

Specification of Letters Patent.

Patented July 24, 1906.

Application filed April 29, 1905. Serial No. 258,052.

To all whom it may concern:

Be it known that I, GEORGE W. YOUNKMAN, a citizen of the United States, residing in the city and county of Denver and State of Colorado, have invented certain new and useful Improvements in Fire-Escapes; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in fire-escapes of the class which may be located within or on the outside of a building, my object being to provide an apparatus of this class which shall be thoroughly automatic in operation, and therefore reliable under all circumstances.

It consists, as shown in the drawings, of a pair of endless cables engaging separated wheels, one pair of wheels being located above and the other below, the distance between the upper and lower wheels being determined by the height of the building to which the apparatus is applied. Instead of cables chains or other suitable flexible devices may of course be employed. The cables are provided with lugs which engage recesses formed in the upper and lower wheels. The apparatus is also provided with transverse rods with which the cables are connected by clamping devices. The cables are also provided with triangular brackets upon which are supported platforms hinged to the transverse rods of the cables. These platforms are so arranged that, on the downwardly-moving side of the cables the platforms are supported in a horizontal position by the brackets, while on the upwardly-moving side of the cables the platforms hang down in a vertical position, since the position of the brackets is reversed and they no longer form a support for the hinged platform. The apparatus is so constructed that the persons who wish to escape from the burning building have only to step upon the platforms and their weight causes the platforms to move downwardly. Suitable governing mechanism is employed to regulate the movement of the apparatus. The necessity for governing means in an apparatus of this class will be readily understood. The platforms travel through a housing, which may be closed at

the front and sides, except where openings are left for people to enter.

Having briefly outlined my improved construction as well as the function it is intended to perform, I will proceed to describe the same in detail, reference being made to the accompanying drawings, in which is illustrated an embodiment thereof.

In the drawings, Figure 1 is a vertical section taken through the apparatus on the line 1 1, Fig. 2. Fig. 2 is a front view of the apparatus with the housing shown in section. Fig. 3 is a side elevation of the upper part of the apparatus, illustrating the governing mechanism. In this view the shaft for the upper pair of wheels is shown in transverse section and the parts on a larger scale. Fig. 4 is a front view of the governing mechanism, shown partly in section and on a scale similar to Fig. 3. Fig. 5 is a top view of the apparatus taken above one of the hinged platforms, the latter being partly broken away. Fig. 6 is a detail side view showing one of the platform-supporting brackets, the platform being shown in the supported position and in section. Fig. 7 is a front view in detail showing one of the brackets and illustrating its connection with other parts of the apparatus. Fig. 8 is a detail view illustrating the manner of connecting the extremities of the cable. Fig. 9 is a similar view looking in the direction of the arrow in Fig. 8 and showing both members of the clamping device, while in Fig. 8 one member is removed. Fig. 10 illustrates the cable shown in connection with one of the lugs carried thereby. Fig. 11 is a view of Fig. 10 looking in the direction of the arrow in the last-named figure.

The same reference characters indicate the same parts in all the views.

Let the numeral 5 designate the individual wheels of the lower pair and 6 the wheels of the upper pair, the two pairs of wheels being engaged by cables 7. The wheels are made fast to upper and lower shafts 8 and 9, the said shafts being journaled in suitable supports 10 and 12. Each cable is provided at suitable intervals with a lug 13, which is semicircular in shape to engage recesses 14 of corresponding shape formed in the wheels 5 and 6. Each lug 13 is provided with a clamping member 15, which co-operates with a clamping member 16, through which bolts 17 are passed, whereby the lug 13 is made fast to the cable. This is best illustrated in Figs. 10 and 11 of the drawings. The man-

22
ner of connecting the two extremities of the cable is illustrated in Figs. 8 and 9, in which two twin members 18 are employed, the same being located on opposite sides of the 5 cable and recessed to receive the latter. These two members are connected by bolts 19. The cable-terminals are passed between these plates and bent outwardly between the two bolts 19, their free extremities being connected outside of the clamping members by a U-bolt 20, whose extremities pass through a plate 21, nuts 22 being applied to the members of the bolt outside of the connecting-plate.

15 Transverse rods 23 are connected with the cables by clamping devices, each composed of two members 24 and 25, connected by bolts 26. Each clamping member 25 is provided with an eye 27, through which the rod 20 23 passes. The rods 23 project beyond the cables (see Fig. 5) and are provided at their outer extremities with rollers 28, which engage channel-iron guides 29, vertically disposed on opposite sides of the apparatus.

25 These rollers and their cooperating guides cause the cables to maintain a practically vertical position between the upper and lower wheels, whereby the cables and their attachments are prevented from swaying either inwardly or outwardly, as might be 30 the case unless guiding means were provided, as just described. Connected with each rod 23 are two brackets 30, each having the shape of a right-angled triangle, one of the 35 sides of each bracket forming the right angle occupying a horizontal position on the downward side of the cables and forming a support for a platform 31, each platform being supported by the two brackets. In order to 40 cause the brackets 30 to maintain their position upon the cables, the brackets are connected directly below the rod 23 with short spindles 32, also provided with rollers, (designated 33.) The inner extremities of these 45 spindles are threaded to receive nuts 34, whereby the brackets are held securely in place on the spindles. This double connection causes the brackets to assume the proper position on the downwardly-moving side of 50 the cables to support the platforms 31 in the operative position, as heretofore explained.

In order to prevent the cables from traveling too rapidly in the event that a considerable number of people are occupying the 55 platforms on the downwardly-moving side of the apparatus, I employ governing mechanism for automatically controlling the movement of the cables, and this mechanism will now be explained.

50 The upper shaft 8, upon which the wheels 6 are mounted, is provided with a gear 35, which meshes with a gear 36, made fast on a counter-shaft 37, journaled in the upright supports 10. Upon one extremity of the 65 shaft 37 is made fast a break-wheel 38, which

is engaged by two break-bands 39 and 40, connected at their upper extremities, as shown at 41, their opposite extremities being connected with the arms 42 and 43 of a triple-armed lever 44, the third arm 45 of the lever 70 being rigidly connected with a bar 46, provided with a weight 47. This bar 46 is pivotally connected with a depending rod 48 on the side of the lever 44 remote from the weight. The lower extremity of this rod is 75 pivotally connected at 49 with a lever 50, fulcrumed at 51 and having its arm on the side of its fulcrum remote from the point 49 pivotally connected with a vertically-inovable rod 52, as shown at 53. This rod 52 80 passes through a tubular column 54 and is provided at its upper extremity with a grooved collar 55, which engages the short arms 56 of two governor-levers 57, fulcrumed at 58 on a rotary device 59, made fast to a short 85 shaft 60, to which is secured a beveled gear 61, meshing with a gear 62, fast on the counter-shaft 37.

Now it will be understood that as the speed of the cables increases the speed of the shaft 90 37, and consequently of the short shaft 60, will also increase, whereby the rotary action of the device 59 will cause the lower weighted extremities of the governor-levers to be thrown outwardly, thus depressing the rod 95 52, raising the rod 48, and moving the lever-arm 46 to cause the arms 42 and 43 of the triple-armed lever to move in the direction indicated by the arrow in Fig. 3, thus tightening both break-belt members 39 and 40, whereby sufficient friction is developed to properly slacken the speed through the instrumentality of the break-wheel 38 and the gearing connection between the shafts 8 and 37.

From the foregoing description the use and 105 operation of my improved device will be readily understood. In the event of a fire or when for any reason it becomes necessary for people to descend to the ground or to the lower floor of the building, where my improved apparatus is located, it is only necessary for them to walk through the openings A of the casing or housing B, inclosing the shafts through which the hinged platforms 31 pass. The mechanism is so arranged that it 110 will be operated by the persons or a single person upon a platform 31, the weight 47, which is adjustable on the bar 46, being so regulated as to permit this. It will be understood that the weight 47 is the normal 115 breaking force of the device when not in use and that the position of this weight, together with its gravity, will determine the sensitivity of the device to weights upon the platforms 31. If it is desired that the normal 120 breaking force shall be increased, the weight 47 will be moved outwardly on the bar 46 or in the direction indicated by the arrow 2 in Fig. 3, while if it is desired that the normal 125 breaking force shall be diminished the weight 130

will be moved inwardly or in a direction opposite the arrow 2 in the same view.

The height of the support 12 for the shaft 9 must be so regulated that as soon as the 5 platforms 31 begin to pass around the wheels 5 with the cables the people upon the platform 31 may easily step from the platform to a suitable support. This may be easily arranged, as will be readily understood. The 10 height of the wheels above the floor or surface upon which the bearings 12 are mounted must of course be sufficient to allow the platforms to pass beneath the wheels. In order to prevent the platforms 31 from falling suddenly upon the brackets 30 after passing over the upper wheels 6, the apparatus is provided with a plate 63, which is attached to an upper 15 floor or support 64 and projects toward the wheels 6, whereby as the platforms pass over 20 the wheels 6, moving in the direction indicated by the arrow at the upper part of Fig. 1, the outer edge of the platform will strike the plate 63, which will support it in an inclined position above the bracket 30 and allow it to approach the bracket gradually.

Having thus described my invention, what I claim is—

1. In a fire-escape, the combination of upper and lower terminal wheels, endless flexible devices mounted on the wheels, brackets hinged to the flexible devices, platforms also hinged to the flexible devices and supported by the brackets, and means for holding the brackets in the platform-supporting position 35 on the downwardly-moving side of the apparatus.

2. In an apparatus of the class described, the combination of upper and lower pairs of terminal wheels, endless flexible devices engaging said wheels, transverse rods connected with the flexible devices, their extremities protruding beyond the said devices and being provided with rollers, vertically-disposed guides engaged by the said rollers, platforms 40 hinged to the said rods, and brackets also pivotally connected with the rods and forming a support for the platforms, the said brackets having spindles at their lower extremities provided with rollers which also engage the vertical guides whereby the brackets are held in the platform-supporting position 45 on the downwardly-moving side of the apparatus, the platforms and brackets being allowed to assume a different position on the 55 upwardly-moving side of the apparatus.

3. In a fire-escape, the combination of upper and lower pairs of terminal wheels, endless flexible devices mounted on the said wheels and provided with lugs adapted to engage recesses formed in the wheels, channel-iron guides mounted on the downwardly-

moving side of the apparatus, rods connected with the flexible devices and protruding beyond the cables into the said guides, brackets connected with the said rods, platforms 65 hinged to the said rods and supported by the brackets in the horizontal position on the downwardly-moving side of the apparatus, the brackets being provided with parts projecting into the channel-iron guides whereby 70 the brackets are held in the platform-supporting position on the downwardly-moving side of the apparatus, substantially as described.

4. In a fire-escape, the combination of upper and lower terminal wheels, endless flexible devices mounted on the wheels and provided with lugs secured to the flexible devices and engaging recesses formed in the peripheries of the wheels, brackets hinged to 80 the flexible devices, platforms also hinged to the flexible devices and supported by the brackets, and means for holding the brackets in the platform-supporting position on the downwardly-moving side of the apparatus. 85

5. In a fire-escape, the combination of upper and lower terminal wheels, endless flexible devices engaging the wheels, transverse rods secured to the flexible devices at suitable intervals, brackets hinged to the rods, platforms also hinged to the rods, means for holding the brackets in place to support the platforms in the horizontal position on the downwardly-moving side of the apparatus, the platforms and brackets being free to assume 95 a changed position on the upwardly-moving side of the apparatus, and suitable governor mechanism for controlling the speed of the apparatus, substantially as described.

6. In an apparatus of the class described, 100 the combination of upper and lower terminal wheels, a shaft upon which the upper pair of wheels is mounted, governor mechanism actuated upon the said shaft for controlling the speed of the apparatus, endless flexible devices 105 mounted on the said wheels, vertically-disposed guides located on the downwardly-moving side of the apparatus, transverse rods connected with the flexible devices and whose extremities engage the said guides, brackets 110 hinged to the said rods and having parts also engaging the guides, and platforms hinged to the rods and held in the horizontal position by the brackets on the downwardly-moving side of the apparatus, substantially as described. 115

In testimony whereof I affix my signature in presence of two witnesses.

GEORGE W. YOUNKMAN.
